UNITED STATES PATENT OFFICE.

GEORGE H. GILMAN AND HENRY M. ROBERTSON, OF ST. PAUL, MINNESOTA.

LIFTING-JACK.

No. 900,720.

Specification of Letters Patent.

Patented Oct. 13, 1908.

Application filed May 18, 1908. Serial No. 433,461.

To all whom it may concern:

Be it known that we, GEORGE H. GILMAN and HENRY M. ROBERTSON, citizens of the United States, residing at St. Paul, in the county of Ramsey and State of Minnesota, have invented certain new and useful Improvements in Lifting-Jacks; and we do hereby declare the following to be a full, clear, and exact description of the invention, such as will enable others skilled in the art to which it appertains to make and use the same.

Our invention relates to lifting jacks of the character disclosed and broadly claimed in the patent to George H. Gilman, No. 810,482, of date January 23, 1906, and has for its object to improve the same in the several particulars hereinafter noted.

To the above ends the invention consists of the novel devices hereinafter described and defined in the claims.

In the accompanying drawings which illustrate the invention, like characters indicate like parts throughout the several views.

Referring to the drawings, Figure 1 is a view in side elevation, with some parts broken away and some parts sectioned and some parts in diagram only, showing our improved lifting jack applied to a car truck.

Figs. 2 and 3 are side elevations of the improved lifting jack; and Fig. 4 is a vertical section taken on the line $x^4 x^4$ of Fig. 2.

The numeral 1 indicates the rails and the numeral 2 the ties of a railway track.

The numeral 3 indicates the wheels, the numeral 4 one of the truck frames, and the numeral 5 the body of a car of standard construction.

Referring more in detail to the parts of the car truck, the numeral 6 indicates the axles to which the wheels are rigidly secured. The numeral 7 indicates the journal boxes and the numeral 8 and 9 indicate, respectively, the bearing brasses and coöperating keys, which parts are of the customary construction and are interposed between the journals of the axles 6 and the tops of the coöperating boxes 7.

The lifting jack shown in the prior patent above identified was in the form of a disk or wheel having an eccentric portion, while the body 10 of the present improved lifting jack is of approximately quadrantal form and is provided with an eccentric, and preferably serrated, rim 11. This quadrantal or segmental body 10 is pivotally connected, pref-

erably by a pin 12, to a bearing head 13, the upper surface of which, as shown, is serrated. At its forward end, the bearing head 13 is provided with an up-turned end or stop lug 14, and at its rear end is formed with a lug seat 15, which latter, in the position of the parts shown in Fig. 3, is adapted to be engaged by a thrust lug 16 of the body segment 10. To afford a pivotal connection between the parts 10 and 13 which will relieve the pivot pin 12 from heavy strains, the lower portion of the bearing head 13 is bifurcated or formed with laterally spaced approximately semi-circular bearing flanges 13^a that 70 embrace an interposed hinge lug or web 10^a of the segment 10. Furthermore, the under edges of the flanges 13^a engage segmental bearing shoulders 10^b formed on the sides of the segment 10 so that the weight of the 75 load on the lifting jack is taken directly between these shoulders and the said bearing flanges 13^a.

The extremity 11^a of the eccentric rim 11 of the segment 10 is much closer to the axis 80 of the pivot 12 than is the other extremity 11^b of said segment. Hence, when the segment is turned into the position shown in Figs. 1 and 2, the bearing head 13 will be dropped much lower down than when said 85 segment is turned into the position shown in Fig. 3. Preferably, when the jack is applied to lift a car frame, the eccentric rim of the segment 10 is placed upon a plank 17 supported by the ties and the head 13 is applied to the bottom of one of the boxes of 90 said truck frame, as shown in Fig. 1. Of course, when the jack is applied, the segment is turned into the position shown in Figs. 1 and 2. Then, when the car is moved forward or in a direction from the left toward the right in respect to Fig. 1, the lifting segment will be moved into the position shown in Fig. 3, thereby raising the axle box to which it is applied so as to permit its bearing 100 brass 8 and key 9 to be easily removed from the box and others, if desired, replaced therein. When the segment reaches its extreme position shown in Fig. 3, the lug 16 of said segment engages the seat 15 of the bearing 105 head 13 and thereby locks the said bearing head against endwise sliding movements on the segment, so as to relieve the pivot pin 12 from undue strains. In fact, when the lug 16 is engaged with the seat 15 as just described, a new or additional point of support 110 between the segment and bearing head is

established, and this, by preventing crowding of the bearing flanges 13^a of the bearing head on the shoulders 10^b of the segment 10, prevents shearing of the pivot pin 12.

5 From what has already been said it will be understood that the bearing rim of the segment 10 is eccentric from one extremity to the other; that is, from the extremity 11^a to the extremity 11^b, its distance constantly increases toward and 10 to the extremity 11^b, so that there will be a continued lift throughout the oscillatory movement of the segment. It is also evident that the bearing head 13, in both extreme positions, is brought into solid engagement with one or the other of the approximately radial edges of the segment 10, so 15 that oscillatory movement of the said lifting segment, when applied in working position, is limited to approximately 90 degrees, although, of course, this feature is capable of considerable variation.

What we claim is:

1. A lifting jack comprising a segment and a bearing head pivotally connected thereto 25 and having engaging bearing flanges and shoulders, and cooperating stop surfaces for limiting the pivotal movements of said parts in respect to each other, the said segment having an eccentric rim portion, the distance of which between the pivotal connection of the two elements increases from one 30 extremity to the other of the said rim, substantially as described.

2. In a lifting jack, the combination with a 35 segment 10 having an eccentric bearing rim

11 and formed with a hinge lug 10^a and with segmental bearing shoulders 10^b, of a bearing head 13 having laterally spaced bearing flanges 13^a embracing and pivotally connected to said lug 10^a and engaging said shoulders 10^b, substantially as described.

3. In a lifting jack, the combination with a lifting segment having an eccentric bearing rim, of a bearing head pivotally connected to said segment, one of the said parts having 45 a lug and the other a co-operating seat located eccentric to the pivotal connection between the two parts and adapted to be engaged when said segment is moved into one extreme position, substantially as described. 50

4. In a lifting jack, the combination with a lifting segment 10 having an eccentric rim 11 and provided with a hinge lug 10^a, bearing shoulders 10^b and lugs 16, of a bearing head 13 having laterally spaced bearing 55 flanges 13^a that embrace and are pivotally connected to said lug 10^a and engage with the said shoulders 10^b, the said head further having a seat 15 adapted to be engaged by the lug 16 when said segment 10 is moved into 60 an extreme lifting position, substantially as described.

In testimony whereof we affix our signatures in presence of two witnesses.

GEORGE H. GILMAN.
HENRY M. ROBERTSON.
